APPARATUS FOR TREATING CANNED GOODS

William de Back, Niagara Falls, N. Y., assignor to Chisholm-Ryder Company, Incorporated, Niagara Falls, N. Y., a corporation of New York

Application June 4, 1937, Serial No. 146,445

8 Claims. (Cl. 198—181)

This invention relates to apparatus for treating canned goods and more particularly to an apparatus for subjecting a continuously moving line of cans or glass jars filled with foodstuff to heat for the purpose of sterilizing the contents of sealed cans or expanding the contents and exhausting all air from unsealed cans.

In general the invention consists of a table having an enclosed compartment through which an endless conveyer moves in a series of passes, the filled containers being placed on the entering part of the endless conveyer and being removed from the discharge end and the cans, while traversing the series of passes or canways being subjected to a heating medium, such as steam, which is supplied through a series of pipes arranged within the compartment, although it will be understood that hot water can also be employed as the heating medium and that under some conditions it may also be desirable to introduce a cooling medium particularly if the foodstuffs are contained in glass jars which are required to be tempered before and after being subjected to sterilizing temperatures.

The principal object of the invention is to provide a simple and inexpensive machine of the character described in which a large quantity of cans are subjected to treatment while traversing the many passes of a chain conveyer within the treating chamber and in which the cans are moved uniformly and without disturbance so that there is no danger of spilling the contents.

Another object of the invention is to employ the steam pipes as the means for guiding the cans in their movement along the numerous canways, the steam pipes being elevated and arranged alongside the canways for this purpose.

Another object of the invention is to provide an overhead housed gear mechanism for driving the drive sprockets of the several conveyer passes, this disposition of the gear case and enclosed gears providing a very simple construction for driving the chain passes and also rendering the gears more accessible for adjustment as well as reducing the danger of water getting into the gear case.

Another object of the present invention is to provide simplified means for supporting the chain passes on sheaves or rollers so that there is no sag and the cans move in a horizontal line throughout the machine. To this end these sheaves or rollers are fast to cross shafts which are journaled on the side walls of the compartment. Alternate opposite moving stretches of the chain conveyer are supported by sheaves on al-

ternate shafts, the alternate stretches of course moving in the same direction and at the same rate of speed. By this means the problem of lubrication of the supporting sheaves is greatly simplified.

Another object of the invention is to provide a simple mechanism for timing the driving sprockets for the several stretches of the conveyer, this timing mechanism permitting of readily taking up and adjusting the chain stretches.

In the accompanying drawings:

Fig. 1 is a top plan view of a machine for heat treating canned goods made in accordance with my invention.

Fig. 2 is a side elevation thereof.

Fig. 3 is a vertical fragmentary longitudinal section, taken on line 3—3, Fig. 1.

Fig. 4 is a fragmentary vertical transverse section, taken on line 4—4, Fig. 3.

Fig. 5 is a fragmentary horizontal section, taken on line 5—5, Fig. 3.

Fig. 6 is a fragmentary vertical longitudinal section, taken on line 6—6, Fig. 1.

Figs. 7 and 8 are fragmentary horizontal sections, taken on the correspondingly numbered lines on Fig. 6.

Fig. 9 is a fragmentary vertical transverse section, taken on line 9—9, Fig. 5.

Fig. 10 is a fragmentary vertical longitudinal section, taken on line 10—10, Fig. 9.

Fig. 11 is a fragmentary horizontal section, taken on line 11—11, Fig. 3.

Fig. 12 is a vertical fragmentary longitudinal section, taken on line 12—12, Fig. 5.

Fig. 13 is a fragmentary vertical diagonal section, taken on line 13—13, Fig. 5.

Fig. 14 is a fragmentary vertical central section through the conveyer.

The compartment or chamber in which the cans 15 are subjected to heat treatment includes a sheet metal box-like end head 16 at the inlet end of the machine which is supported in any suitable manner by standards 17, a box-like sheet metal section 18 at the opposite end of the machine and supported by standards 19 and an intermediate channel shaped section 20 connecting the box-like end sections or heads 16 and 18, the open sides of the box-like end sections 16 and 18 opening toward one another so that the sections 16, 18 and 20 form a trough-like compartment 21. The central section 20 is preferably additionally supported at its center by standards 22 in any suitable manner. Between the end heads 16 and 18 the central portion 20 is covered with a series of removable covers 25, 55

these covers permitting access to the chamber 21, and the bottom of the central section 20 preferably inclines to a central drain channel 26 from which the condensate or water can be removed through an opening closed by a drain plug 21. The steam for heating the interior of the compartment 21 is supplied to a steam manifold 30 which extends transversely across the chamber at its center and through one of the side walls, as best shown in Figs. 2 and 9. At spaced intervals this manifold 30 carries upwardly extending nipples 31 each of which discharges the steam into a horizontal tube 32 extending the full length of the central section 20, as best shown in Fig. 3. These tubes 32 are provided at spaced intervals with a plurality of orifices 33 through which the steam is discharged and each end of the tubes 32 is carried by a support 34 in the form of a vertical sleeve 35 formed with a stud 36 which projects into the end of the tube 32 which it supports. At the inlet end of the machine the sleeves 35 are mounted on a cross bar 37 by means of vertical bolts 38, the ends of the angles 37 being secured to the side walls of the central section 20 in any suitable manner. At the discharge end of the machine the sleeves 35 are mounted on a similar cross bar 39 by vertical bolts 40, the cross angle being supported by the side walls of the end head 18 in any suitable manner. Each of the supporting members 34 is also formed to provide a bifurcated jaw 41 which projects horizontally in the opposite direction from the stud 36 which supports the corresponding pipe end.

35 The longitudinal steam pipes 32 define and provide side guides for a plurality of canways through which the cans are conveyed back and forth and around the ends of the steam pipes in serpentine fashion by a conveyer chain 45. This chain, as best illustrated in Fig. 14, consists of a plurality of U-shaped links 46, the legs 47 and 48 of each of which are joined by a cylindrical connecting portion 49 and the ends of the legs 47 and 48 of each link being joined to the cylindrical portion of the next succeeding link by a vertical pivot pin 50. To the upper leg 47 of each link is welded a diamond shaped horizontal support 51 which extends transversely of the link and is adapted to support the bottom of a can placed thereon, the supports 51 being diamond shaped so as to pass around the chain sprockets.

55 At the feeding end of the machine the several stretches of the chain pass around idler sprockets 55. Each of these sprockets 55 is loosely mounted on a vertical post 56 which is carried at its upper and lower ends by a U-shaped bracket 57. The base 58 of each of the brackets 57 is formed to provide guideways 59 by which the brackets 58 are slidably supported, for movement lengthwise of the machine, on brackets 60 secured in any suitable manner to the end head 16. Each of the brackets 57 is yieldingly urged outwardly by a spring 61 which is interposed between a flange 62 at the outer end of the base 58 of the bracket and a nut 63 of an adjusting bolt 64 which extends through the spring 61 and flange 62 and through the end wall of the end head 16, as best illustrated in Fig. 3. The nut 63 is held against rotation by the base 58 and it will therefore be seen that by turning the bolt 64 the spring 61 is compressed to urge the bracket 57 outwardly or toward the end wall of the end head 16, thereby placing the stretches of chain

which pass around the corresponding sprocket 58 under yielding tension.

Each of the brackets 57 also carries a semi-circular guide 65 for guiding the cans as they pass around the sprockets 55 in their course through the chamber 21. The guides 65 are preferably arranged in the same plane as the steam pipes 32 and each end thereof extends into the bifurcated jaw 41 of one of the supports 34, as best shown in Fig. 5. It will be seen that by this construction the cans on the diamond shaped supporting plates 51 of the chain are guided by the steam pipes along the stretches of the chain and are guided around the idler sprockets 55 by the semi-circular guides 65 and the bifurcated jaws 41. The ends of the chain stretches at the discharge end of the machine pass around and are driven by sprockets 70. Each of these sprockets 70, as best shown in Fig. 6, is keyed to a vertical shaft 71 which is journaled at its lower end in a bearing bracket 72 and extends upwardly through and is journaled in an overhead gear case 73. The several shafts 71 are driven in unison by a cross worm shaft 74 which can be supported at intervals by split bearings 75 and is shown as driven by a drive sprocket 76 and drive chain 77, through which power is applied for turning the worm shaft 74. Number of worms 78 corresponding in number and location to the shafts 71 are mounted on the worm shaft 74 and each of these worms engages a worm wheel 79 loosely mounted on the corresponding vertical shaft 71, as best shown in Fig. 6. The hub 80 of each of the worm wheels 79 extends through a bearing 81 in the top of the gear case 73 and is provided with an annular series of vertical pin holes 82. To the upper end of each of the vertical shafts 71 is keyed a collar 83 having a vertical hole 84 which is arranged to register with any of the pin holes 82. The drive between each of the worm wheels 79 and its shaft 71 is established by a removable pin 85 which extends through the hole 84 into one or another of the pin holes 82, as best shown in Fig. 6.

The upper end of each shaft 71, together with its collar 83 and adjusting pin 85 is preferably enclosed by a cap 86 which fits over the upper end of the corresponding bearing 81.

It will be seen that by removing the pins 85 the several stretches of the chain can be adjusted relative to the vertical drive shafts 71 and that therefore the several drive sprockets 70 can be timed with reference to one another and the slack in one or more of the chain stretches taken up. This is accomplished by the simple expedient of removing one or more of the pins 85 and adjusting the chain stretches after which the pins 85 are reset to maintain this adjustment.

The cans on the conveyer chain are guided around the drive sprockets 70 by a plurality of semi-circular guides or rails 87 which are secured at their centers to the end wall of the end head 18 in any suitable manner and the ends of which fit into the bifurcated jaws 41 of the supports 35, as best shown in Fig. 5. It will be seen that at the drive ends of the chain stretches the cans on the diamond shaped plates 51 are guided around the bends by the guide rails 87 and jaws 41 so that the cans cannot become displaced. The discharge end of the last canway is formed by a semi-circular guide rail 88 which is secured to the end wall of the section 18 and a V-shaped discharge bracket 89 which is mounted on the side wall of the end head 18 next to the bracket 75.

88. The discharge bracket prevents the cans from passing onto the final stretch of the chain and instead discharges these cans through a can discharge opening 90.

5 The chain is introduced into the chamber 21 through an inlet opening 91 in the end wall of the end head 16 and emerges from this chamber through an opening 92 at the opposite end of this same end wall. The emerging chain passes 10 around a sprocket 93 which is loosely mounted on a pin 94, this pin being suitably supported by a bracket 95, as best shown in Fig. 13. This pin 94 also carries a swinging arm 96 on the outer end of which is loosely mounted a sprocket 97 15 which bears against the chain so as to act as a tightener. For this purpose a spring 98 is anchored at one end to the end wall of the end head 16 and at its other end is connected to a screw eye 99 which extends through the end of the arm 96 and is provided with a nut 100 bearing against this arm and by means of which the tension of the spring 98 in urging the sprocket 97 against the chain can be adjusted. The length of chain emerging from the opening 92 and entering the opening 91 serves as a feed stretch and to facilitate the placing of cans upon this stretch it is surrounded by a horizontal guide rail 105 which can be secured to the end head 16 in any suitable manner. Adjacent the inlet opening 91 an inner 20 guide rail 106 is also provided, the rails 105 and 25 106 forming a canway 107 into which the cans are conveniently placed on the chain which is there supported by sprockets 108 and 109 and carries them through the inlet opening 91 and 30 back and forth along the several canways until the cans engage the V-shaped discharge bracket 89 located at the diagonally opposite corner from the inlet opening 91, as best shown in Fig. 5.

On being discharged from the can discharge opening 90 the cans are picked up by any suitable discharge means, such as the discharge wheel 110 which is shown as rotatably mounted on a pin 111 carried by a bracket 112. As best shown in Fig. 12 a sprocket 113 is fast to the discharge wheel 110 and is driven by a sprocket 114 fast to that drive sprocket 70 which is nearest the discharge opening 90.

In handling unsealed cans it is essential that the stretches of the conveyor chain within the chamber 21 be supported at close intervals so that the chain does not sag and spill the contents of the cans. To this end those stretches of the chain which travel toward the feeding end of the machine are supported at intervals on sheaves 115. These sheaves 115 are arranged in transverse alignment in rows along the machine and each of the sheaves 115 is fast to a transverse shaft 116. The several stretches, of course, all move at the same rate of speed.

60 Similarly, those stretches of the conveyor chain traveling toward the discharge end of the machine are supported at spaced intervals by sheaves 120 which are arranged in transverse alignment, each row being fast to a shaft 121. Each end of each of the shafts 116 and 121 is supported by any suitable form of bearing carried by the side walls of the central section 20. Preferably each of these bearings, as best shown in Fig. 10, consists of a pair of rollers 125 and 126 65 mounted to project outwardly from a plate 127 which is secured to the corresponding wall of the central section 20 and the end of each shaft rests jointly on the rollers 125 and 126. These rollers 125 and 126 preferably revolve in a bath 70 of oil 128 which is provided by mounting an oil

cup 129 below each bracket 127, the rim of this cup extending upwardly to embrace the rollers 125 and 126. It will be seen that this form of bearing provides an inboard bearing for each end of each of the shafts 116 and 121 which can be very easily lubricated and further that the assembly of these shafts and the sheaves carried thereby is very simple.

5 From the foregoing it will be seen that the present invention provides a very simple and inexpensive construction in that the steam pipes are used as the guides at the sides of the canways and are connected with the curved rails at the ends of the canways in a simple and effective manner. Further, it will be seen that by the provision of an overhead gear case with its contained drive mechanism a very simple form of drive for the several stretches of chain is provided and at the same time the adjusting pins 85 for taking up the chain links are readily accessible. Also 10 it will be seen that the provision of these adjusting pins provides a very simple and quick method of accurately taking up the slack in the chains. It will further be seen that by mounting the supporting sheaves fast to cross shafts and journaling the ends of these cross shafts in bearings at the sides of the compartment a very simple and inexpensive construction of chain support is provided which prevents appreciable sag in the 15 chain stretches.

30 I claim as my invention:

1. In apparatus of the character described, a supporting frame formed to provide a treating chamber, a flexible endless conveyer adapted to convey the articles to be treated through said chamber, said conveyer being formed within said chamber to provide a series of serpentine passes each supported at one end by a driving wheel and at its opposite end by a driven wheel, a drive mechanism for rotating said series of driving 35 wheels in unison and means for detachably connecting each of said driving wheels to said drive mechanism whereby said driving wheels can be adjusted relative to one another to adjust the several passes of said conveyer.

2. In apparatus of the character described, a supporting frame formed to provide a treating chamber, a flexible endless conveyer adapted to convey the articles to be treated through said chamber, said conveyer being formed within said 50 chamber to provide a series of serpentine passes each supported at one end by a driving wheel and at its opposite end by a driven wheel, a shaft fast to and projecting outwardly from each of said driving wheels, a drive gear loosely mounted 55 on the projecting end of each of said shafts, means for driving said drive gears in unison and manually releasable means for connecting each drive gear with the shaft on which it is mounted.

3. In apparatus of the character described, a 60 supporting frame formed to provide a treating chamber, a flexible endless conveyer adapted to convey the articles to be treated through said chamber, said conveyer being formed within said chamber to provide a series of serpentine passes each supported at one end by a driving wheel and at its opposite end by a driven wheel, a shaft fast to and projecting outwardly from each of said driving wheels, a drive gear loosely mounted on the projecting end of each of said shafts, 65 means for driving said drive gears in unison and manually releasable means for connecting each drive gear with the shaft on which it is mounted comprising a collar fast to each shaft and a manually movable pin carried by said collar and 70 75

adapted to enter one of a series of openings provided in said gear.

4. In apparatus of the character described, a supporting frame formed to provide a treating chamber, a horizontal endless flexible conveyer adapted to convey the articles to be treated through said chamber, said conveyer being formed within said chamber to provide a series of serpentine passes each supported at one end 5 of said chamber by a driving wheel rotating about a vertical axis and at the opposite end of said chamber by a driven wheel rotating about a vertical axis, a drive mechanism for rotating said series of driving wheels in unison and means for 10 detachably connecting each of said driving wheels to said drive mechanism whereby said driving wheels can be adjusted relative to one another to adjust the several passes of said conveyer. 15
5. In apparatus of the character described, a supporting frame formed to provide a treating chamber, a horizontal endless flexible conveyer adapted to convey the articles to be treated through said chamber, said conveyer being formed within said chamber to provide a series 20 of serpentine passes each supported at one end of said chamber by a driving wheel rotating about a vertical axis and at the opposite end of said chamber by a driven wheel rotating about a vertical axis, a shaft fast to and projecting upwardly 25 from each of said driving wheels, a drive gear loosely mounted on the upper end of said shaft, means for driving said drive gears in unison and manually releasable means connecting each drive 30 gear with the shaft on which it is mounted. 35
6. In apparatus of the character described, a supporting frame formed to provide a treating chamber, a horizontal endless flexible conveyer adapted to convey the articles to be treated through said chamber, said conveyer being formed within said chamber to provide a series 40 of serpentine passes each supported at one end of said chamber by a driving wheel rotating about a vertical axis and at the opposite end of said chamber by a driven wheel rotating about a vertical axis, a shaft fast to and projecting upwardly 45 from each of said driving wheels, a drive gear loosely mounted on the upper end of said shaft, means for driving said drive gears in unison and manually releasable means connecting each drive 50 gear with the shaft on which it is mounted, comprising a collar fixed to each shaft above said drive gear and a manually movable pin carried by said collar and adapted to enter one of a series of openings provided in said gear.
- 55 7. In apparatus of the character described, a

supporting frame formed to provide a treating chamber, a horizontal endless flexible conveyer adapted to convey the articles to be treated through said chamber, said conveyer being formed within said chamber to provide a series 5 of serpentine passes each supported at one end of said chamber by a driving wheel rotating about a vertical axis and at the opposite end of said chamber by a driven wheel rotating about a vertical axis, a gear case extending transversely of 10 said frame and arranged above the series of driving wheels, a drive shaft journaled in said gear case and extending lengthwise thereof, and means operatively connecting said drive shaft with each of said driving wheels to drive them in unison, 15 comprising a vertical shaft fast to each of said driving wheels, said shafts extending upwardly and being journaled in said gear case, a worm wheel loosely mounted on the upper end of said drive shaft and journaled in and projecting upwardly 20 from the upper wall of said gear case, a plurality of worms on said drive shaft and each meshing with one of said worm wheels, and manually releasable means for connecting each worm wheel with the shaft on which it is mounted 25 comprising a collar fixed to each shaft above its worm wheel and a manually movable pin carried by said collar and adapted to enter one of a series of openings provided in said gear.

8. In canning apparatus of the character described, a supporting frame formed to provide a treating chamber, a horizontal endless flexible conveyer, a series of can carrying members mounted on and arranged above said conveyer and adapted to convey the articles to be treated 30 through said chamber, said conveyer being formed within said chamber to provide a series of serpentine passes, the alternate stretches of which are parallel and move in opposite directions, means for propelling said conveyer and 35 means for supporting said stretches comprising two series of shafts each journaled at its ends in the sides of said chamber and each shaft of one series carrying a plurality of grooved sheaves, the grooves of said sheaves receiving the conveyer 40 stretches moving in one direction and engaging and directly supporting the series of can carrying members mounted thereon and each shaft of the other series carrying a plurality of similar sheaves receiving the conveyer stretches moving 45 in the opposite direction and directly supporting the series of can carrying members mounted 50 thereon.

WILLIAM DE BACK.
